FISHING TOOL

Charles F. Moseley, Bartlesville, Okla.

Original application June 26, 1936, Serial No. 87,579. Divided and this application August 25, 1937, Serial No. 160,923

12 Claims. (Cl. 294—96)

The present application is a division of my application Serial No. 87,579 filed June 26, 1936. In the parent application I have disclosed improvements in tubing catchers or tubing stops and also a novel spear or fishing tool. The present application is filed for the purpose of specifically claiming said spear or fishing tool.

In many spears now in use, a solid cone or mandrel is mounted on a tubing or rod string and is used to spread a slip assembly so that the slips will engage the wall of the stuck tubing or casing at the desired point; the pull of the tubing or rod string then acting on the cone to retain the slips in their spreaded position. The use of such devices is subject to at least one major difficulty, which it is the purpose of my invention to overcome. When the tubing or rod string has been pulled and the cone pressed against the slips, causing the teeth of the latter to engage the casing, such cones, because of the relatively large surface area thereof, which is in contact with the back of the slips, and after remaining in the well for a long period of time subject to corrosive and rusting action of well fluids, are wont to "freeze" to the slips, and oppose effort to withdraw the same from engagement with the slips so that the slips may be collapsed to permit the entire structure to be removed from the well or to be reset at another point in the well casing.

It is the principal object of my invention to provide a spear having a form of collapsible cone made in segments on which the slips are slidable, and which are in turn acted upon by a spreader plate or mandrel to force the teeth on the slips into engagement with the well casing. Said spreader plate or mandrel is in the form of a relatively flat frustum of a cone, the periphery of which may be smooth or formed in a series of steps or shoulders, or otherwise, so that the total amount of the surface of the mandrel contacting the corresponding surfaces of the collapsible cone segments is relatively much less than the case of the solid cones heretofore used, and the danger of "freezing" of the slips will thereby be greatly minimized.

Another object of my invention is to furnish a fishing tool which will function in a highly efficient manner for the withdrawal of casing or tubing from a well, and one which may be readily disengaged from the casing or tubing while down below the surface of the ground.

With the foregoing objects outlined and with other objects in view which will appear as the description proceeds, the invention consists in the

novel features hereinafter described in detail in connection with the accompanying drawings and more particularly pointed out in the appended claims.

In the drawings:

Fig. 1 is an elevation, partially in vertical section of a form of my invention showing slips in the collapsed position for free movement within the well casing.

Fig. 2 is a similar view of the device in operative position anchored within the well casing.

Fig. 3 is a detail of the latching slot for holding the slips in the collapsed or engaging position.

Fig. 4 is a detail of one of the segments of the collapsible cone.

Figs. 5, 6 and 7 are sections taken along lines 5—5, 6—6 and 7—7 respectively, of Fig. 1.

Like numbers indicate like parts in the several drawings.

Referring to Fig. 1, there is shown a section of well bore or casing 10 in which is inserted a section of well string or tubing 11 adapted to be set or anchored in casing 10 on which is mounted the device of my invention, which consists of an elongated sleeve member 12 surrounding tubing 11 and spaced therefrom a suitable distance so as to form a generally annular chamber between tubing 11 and sleeve 12. Extending from the inner wall of sleeve 12 toward tubing 11 is a ring 13 surrounding tubing 11 but not in contact therewith. Ring 13 divides the annular space between tubing 11 and sleeve 12 into an upper chamber 14 and a lower chamber 15. In the chamber 14 is a coil spring 16 surrounding tubing 11 and held in place against ring 13 by a follower 17 which is fixedly mounted on tubing 11 and extends into the upper end of chamber 14. The outer surface of chamber 14 is of angular contour, as in the form of a square, and the outer surface of follower 17 is complementary in shape (see Fig. 7) to permit telescoping of follower 17 into chamber 14 while preventing turning of sleeve 12 relative to follower 17 and to thereby cause sleeve 12 to turn with tubing 11 since follower 17 is fixedly attached to tubing 11. A cage 18 on which are mounted bow springs 19 surrounds the lower portion of sleeve 12, and lugs 20 extend inwardly from the lower end of cage 18 and engage inverted L shaped slots 21 (Fig. 3) located in about the center of sleeve 12 and serve to hold cage 18 in engagement with sleeve 12, and slots 21 cooperate with lugs 20 to limit the vertical and lateral movement of cage 18 with relation to

sleeve 12. Bow springs 19 are adapted to frictionally engage the inner walls of casing 10, the tension of bow springs 19 being sufficient to support the weight of cage 18 by frictional pressure exerted by springs 19 against the walls of casing 10.

The lower end of sleeve 12 terminates in an annular skirt 22 which is of inverted U shape in diametrical section. The outer prong of the U turns inwardly toward tubing 11 forming an annular lip 23 tending to partially close the opening of the U thus forming an annular groove 24 in the lower end of sleeve 12, said groove opening downwardly. A series of arc shaped plates 25 forming a collapsible cone are suspended from skirt 22 by means of tongues 26 having outwardly turned lips which engage the inwardly extending lips 23 forming a hinge type joint which permit plates 25 to swing toward or away from casing 10. Plates 25 are spaced apart a sufficient distance to permit of movement of plates 25 towards each other when they move in a direction away from the walls of casing 10 in assuming the collapsed position of Fig. 1. All of the plates 25 together form the collapsible cone which is one of the principal features of my invention. The maximum spread of plates 25 is regulated by means of straps 28, each of which has one end fixedly attached to one of plates 25 by means of a bolt 29 and the other end attached to an adjacent plate 25 by means of another bolt 30 which is slidably engaged in a slot 31 in strap 28. (Fig. 4.) By this means plates 25 may swing inwardly toward tubing 11 to the extent permitted by slots 31 in straps 28 and outwardly toward casing 10 to the same extent. The maximum outward movement of plates 25 is such that the maximum outside diameter of the cone formed by plates 25 in their most extended position will be less than the inside diameter of casing 10.

The lower edges of plates 25 are tapered downwardly and outwardly in a series of circular steps or seats 32. A mandrel 33 fixedly attached to tubing 11 above the plates 25, is formed in the shape of a frustum of a cone, the outer surface of which is tapered inwardly and upwardly in a series of circular steps or shoulders 34 adapted to be seated in seats 32 when mandrel 33 is brought into contact with plates 25. As noted above, the lower edges of plates 25 may form a smooth conical seat and the outer surface of mandrel 33 may have a corresponding shape. The taper of the lower edges of plates 25 may be greater than that of mandrel 33 so that the points of contact of plates 25 with mandrel 33 will form a narrow ring. Or in the case of the step-wise taper illustrated, will form a series of concentric contact rings. The chief point to be noted is that the total surface thus in contact between plates 25 and mandrel 33 is kept very small for reasons to be more fully explained hereinafter.

A ring 35 suspended from cage 18, encompasses sleeve 12 between cage 18 and the skirt 22 of sleeve 12 and is slideable on sleeve 12. Attached to ring 35 by resilient arms 36 and extending therebelow are toothed arc-shaped slips 37. The inner faces of slips 37 form surfaces tapering upwardly and complementary in shape to the outer faces of plates 25, with which they are in slideable engagement. Lugs 39 extend from the inner faces of slips 37 through elongated slots 40 formed in plates 25 which limit the movement of slips 37 over plates 25 to a vertical direction. Slots 40 are of sufficient length to permit the maximum required amount of such movement.

Heads 41 on lugs 39 prevent disengagement of slips 37 from plates 25.

In the device illustrated, ring 35 and the lower end of cage 18 are joined together to form a swivel joint, and mandrel 33 carries a spear point 43 to aid in guiding the device into casing 10. When the device of my invention is to be used as a fishing tool it is inserted into the casing or tubing to be pulled in the position shown in Figs. 1 and 2.

When used as a fishing tool, the device functions in the following manner:

When the device is in the collapsed position of Fig. 1, lugs 20 are engaged in the lateral arms of slots 21 in which position the slips 37 are positioned on plates 25 at a point closest to the end member 22 of sleeve 12. When the device has been inserted in casing 10 to the desired position therein, tubing 11 is turned to disengage lugs 20 from the lateral arms of slots 21 and lugs 20 are thereby moved into the vertical arms of slots 21, whereupon a lift or pull is taken on tubing 11. The upward movement of tubing 11 will cause plates 25 to move up over slips 37 and the outward taper of plates 25 will force slips 37 toward the 35 walls of casing 10 until their teeth bite into the walls of casing 10. The continued upward movement of tubing 11 will bring pressure to bear through mandrel 33 on the contact surfaces of plates 25 and will thus act to firmly press the 30 teeth on slips 37 into the walls of casing 10 and will hold the slips in firm engagement with casing 10 as long as the pull is exerted on tubing 11. When it is desired to release the hold of the device on casing 10, the pull on tubing 11 is slackened 35 and tubing 11 is permitted to start downward into casing 10, whereupon follower 17 will act upon spring 16 compressing it sufficiently to permit mandrel 33 to move downward out of engagement with seats 32 on plates 25. Thereupon plates 25 40 will collapse permitting slips 37 to spring inwardly pulling the teeth out of engagement with casing 10. Spring 16 will then expand forcing plates 25 down over slips 37 and bring seats 32 again into contact with shoulders 34 on mandrel 33 and will 45 at the same time bring lugs 20 upward in slots 21 until lugs 20 register with the lateral arms of slots 21 thereupon tubing 11 is turned sufficiently to engage lugs 20 in the lateral arms of slots 21 locking slips 37 in the collapsed or inoperative 50 position in exactly the same manner as described above. The entire device may then be withdrawn from casing 10.

Here again it will be evident that even though plates 25 may tend to "freeze" to slips 37, compression of spring 16 will permit mandrel 33 to move out of contact with seats 32 a distance sufficiently great to permit slips 37 and plates 25 to collapse inwardly toward tubing 11 as a result of the tension in the walls of casing 10 and thus 60 free slips 37 from the walls of casing 10.

It will be evident that numerous modifications may be made in the elements of my device. For example, mandrel 33, instead of being solid as shown, may be in the form of a spider with spaces 65 between the arms thereof to permit ready passage of well fluids therethrough. In this form there may be one or more arms of the spider in contact with each of the plates 25 in which case the area of contact between the spider arms and plates 25 will consist of a series of arcs. From a practical standpoint it is only necessary that the arms of the spider shaped mandrel be sufficiently strong to support the weight of the tubing and sufficiently stiff to prevent the tension in 75

the walls of casing 10 from forcing plates 25 inwardly by overcoming the resistance of the spider arms to such movement.

5 The number of slips 37 and cone segments or plates 25 may be varied as desired depending upon the size of the casing with which the device is to be used.

10 Tubing 11 may be replaced by a solid metal member or part of a rod string to obtain greater strength.

15 In the form of my new device illustrated herein, arms 36 attached to rings 35 and supporting slips 37 are shown as flat bars. These may be spring steel to allow sufficient outward spring 20 of slips 37 in order that slips 37 may engage casing 10 and also to assist in causing slips 37 to pull out of engagement with casing 10 when the pressure of the tubing is removed. Also arms 36, instead of being solidly attached to ring 35 25 as shown, may be attached thereto by a hinge device.

25 Various other modifications in shape, size and form of the elements of the device will no doubt be apparent to those skilled in the art without occasioning a departure from the scope of my invention as set forth in the appended claims.

30 What I claim and desire to secure by Letters Patent is:

1. In a device of the character described, a well string, a collapsible cone comprising segmental members suspended on said string, slips 35 slidably engaging said cone, means secured to the lower end of the well string for holding said cone in expanded condition, said means being movable downwardly away from the cone to allow the latter to collapse toward the well string, the last-mentioned means including a substantially disc-shaped mandrel engageable with the lower end portions of the segmental members, and a 40 spear head depending from the mandrel.

2. In a fishing tool of the class described, a well string, a collapsible cone comprising segmental members suspended on said string, the small end of the cone being uppermost, slips 45 slidably engaging said cone, means secured to the lower end of the well string and at the lower ends of the segmental members for holding said cone in expanded condition, said means being movable axially downwardly of the well string 50 away from the cone to allow the latter to collapse toward the well string, and a spear head depending from the mandrel.

3. In a fishing tool of the character described, a well string, a collapsible cone comprising segmental members suspended on said string, the small end of the cone being uppermost, slips 55 slidably engaging said members and adapted to interlock with the bore of a well, means secured to the lower end of the well string, arranged at the lower ends of said members and movable axially of the well string into and out of engagement with the lower end portions of said segmental members for holding the cone in expanded condition, and a spear head depending from the 60 mandrel.

4. A fishing tool of the character described, comprising a well string, a collapsible cone comprising segmental members suspended on said string, the small end of the cone being uppermost, slips 70 slidably engaging said members and adapted to interlock with the bore of a well, means secured to the lower end of the well string, arranged at the lower ends of said members and movably axially of the well string into and out 75 of engagement with the lower end portions of

said segmental members for holding the cone in expanded condition, a spear head suspended from said means, and means actuated by movement of the string relatively to said members for setting and releasing said slips.

5. In a device of the character described, a well string, a follower supported thereby, a sleeve 10 slidably mounted on the string, a spring 15 co-acting with the sleeve and follower for normally urging the sleeve downwardly, a cage mounted 15 on the sleeve and provided with friction means engageable with a bore of a well for holding the cage in a fixed position while the sleeve is moved relatively thereto, a slip assembly carried by and depending from the cage, a collapsible cone suspended from the sleeve and including segmental members slidably engaging the slips, and means supported by the well string and positioned at the lower ends of the segmental members for holding the cone in expanded condition. 20

6. In a fishing tool of the character described, a well string, a sleeve member slidable thereon, a collapsible cone including segmental members hingedly connected to the lower end of the first-mentioned member, a slip assembly having slips 25 slidably engaging the segmental members and adapted to interlock with a well casing, a substantially disc-shaped mandrel secured to the lower end of the well string and engageable with the lower ends of the segmental members for 30 normally holding the cone in expanded condition, said mandrel being movable downwardly away from the cone to allow the latter to collapse, and a spear head depending from the 35 mandrel.

7. In a fishing tool of the character described, a well string, a member supported by the string, a collapsible cone including segmental members, each having its upper end hingedly connected to the first-mentioned member, toothed slips 40 slidably engaging the cone and adapted to grip the bore of a well casing, a substantially disc-shaped mandrel secured to the lower end of the well string, arranged at the lower ends of said segmental members and having a relatively short 45 annular surface engageable with the lower end portions of the segmental members for holding the cone in expanded condition, said mandrel being movable downwardly away from the segmental members to allow the cone to collapse, 50 and a spear head depending from said mandrel.

8. In a structure of the character described, a well string, a sleeve supported by the string, a collapsible cone including segmental members, each having its upper end hingedly connected to 55 the lower end of the sleeve, toothed slips slidably engaging the segmental members, slot and pin connections joining the slips to said members, means mounted on the sleeve and adapted to frictionally engage the bore of a well for setting 60 and releasing said slips, a substantially disc-shaped mandrel secured to the lower end of the well string and adapted to engage the lower end portions of the segmental members for normally holding the cone in expanded condition, said tubing being movable with the well string relatively 65 to said cone for releasing the mandrel from the cone to permit collapsing of the latter, and a spear head depending from the mandrel.

9. In a structure of the character described, a 70 well string, a sleeve supported thereby and movably arranged relatively to the well string, a cage, a slot and pin connection joining the cage to the sleeve, friction means carried by the cage and engageable with the bore of the well for 75

- holding the cage in a fixed position while the sleeve moves relatively thereto, a slip assembly connected with and suspended from the cage, toothed slips forming part of said assembly and adapted to be set by movement of the sleeve relatively to the cage and slip assembly, a collapsible cone including segmental members, each having its upper end hingedly connected to the lower end of the sleeve, said slips slidably engaging said segmental members, and a mandrel supported by the tubing string and engageable with the lower end portions of the segmental members for normally holding the cone in expanded condition.
- 15 10. A fishing tool of the character described, comprising a well string, a collapsible cone supported by the string and comprising segmental members, said cone having its small end uppermost, means hingedly supporting said members from the upper ends thereof, toothed slips slidably engaging said members, means arranged above the members for setting said slips, a relatively short mandrel secured to the lower end of the well string and engageable with the lower end portions of said members for normally holding the cone in expanded condition, and a spear head depending from said mandrel.
- 20 11. A fishing tool of the character described, comprising a supporting structure, a collapsible cone supported by said structure and comprising pendant segmental members, each having its

upper end hingedly connected to the supporting structure, toothed slips slidably engaging said segmental members, a relatively short mandrel secured to the lower end portion of the supporting structure and engageable with the lower end portions of the segmental members for holding the cone in expanded condition, and a spear head depending from said mandrel. 5

12. A fishing tool of the character described, comprising a supporting structure, a follower mounted on said structure, a sleeve surrounding the supporting structure and having an internal shoulder, a spring surrounding the supporting structure and arranged between the follower and shoulder for urging the sleeve downwardly, a cage surrounding said sleeve and having internally extending lugs, the sleeve having inverted L-shaped slots into which the lugs extend, friction springs secured to the cage and engageable with the bore of the well for supporting the cage independently of the sleeve, a slip assembly connected to and suspended from the cage and including a plurality of toothed slips, a collapsible cone comprising segmental members hingedly suspended from the lower end of the sleeve, said slips slidably engaging the segmental members, and a mandrel carried by the supporting structure and engageable with the lower end portions of the segmental members for holding the cone in expanded condition. 15 20 25

CHARLES F. MOSELEY. 30
